Morris Cohen, INVENTOR.

ATTORNEY.

UNITED STATES PATENT OFFICE.

MORRIS COHEN, OF NEW ORLEANS, LOUISIANA.

TAG ATTACHMENT FOR PACKAGE CLOSURES.

1,405,289.

Specification of Letters Patent. Patented Jan. 31, 1922.

Application filed June 28, 1921. Serial No. 480,992.

To all whom it may concern:

Be it known that I, MORRIS COHEN, a citizen of the United States, residing at New Orleans, in the parish of Orleans and State 5 of Louisiana, have invented certain new and useful Improvements in a Tag Attachment for Package Closures, of which the following is a specification.

This invention relates to attachments for 10 parcel post package closures and other packages which are subject to inspection of the contents.

The object of the invention is to provide 15 an attachment for a closure of this character, for connecting to said closure a tag furnished by the Government.

Another object is to provide a connector of this character which may be easily applied to such closure and which is equipped 20 with a suitable fastener for the parcel post tag.

Another object is to provide a simple and cheap device of this character which when applied will not in any way interfere with 25 the operation of the closure.

With these and other objects in view, the invention consists in certain novel features of construction as hereinafter shown, described and claimed.

30 In the accompanying drawings:

Figure 1 represents a rear elevation of a package shown with a parcel post closure applied with this improved attachment used in connection therewith.

35 Fig. 2 is a rear elevation or inside view of the closure with this attachment applied; and

40 Fig. 3 is a detail perspective view of one of the fasteners employed in connection with the attachment.

The attachment constituting this invention is designed especially for use in connection with the package fastener or closure shown in the patent to A. H. Swett No. 45 1,309,492 issued July 8, 1919 though it is not to be restricted for use in connection with this fastener only.

In the embodiment illustrated in the drawing, the fastener to which this attachment is 50 applied, is the same as that shown in the patent above referred to and comprises two similar pieces of substantial paper stock A and B, the under sides of which carry an adhesive as indicated by the stippling in 55 Fig. 2, and the stock from which these pieces are composed is sufficiently pliable to permit

its being readily laid over and flattened down upon varying package surfaces. As shown, these two pieces A and B are adapted to meet end to end and are preferably stiffened along the meeting edges by strips *a* and *b*, which also may be of paper. These stiffening strips have no adhesive applied to their undersides but together with the portions of the pieces A and B with which they are related constitute the flaps of the fastener. The flaps of the members A and B are provided with suitable metal clips *c*.

The complete fastener may be made up as shown in Fig. 2 with the metal clips in 70 place and completely closed so that the article is ready for application to a box or package by merely moistening the gummy surfaces, of the pieces A and B and properly locating the fastener and forcing it upon 75 the box or package.

The device constituting this invention, which is designed for fastening to one of the members A or B the Government tag shown at T, comprises a strip 1 of paper stock or 80 other suitable fabric, which is of a length greater than the width of the member A to which it is applied and which is secured thereto adjacent one of the reinforcing members, as is shown clearly in Figs. 1 and 2. 85 The projecting end of this strip 1 has an eyelet 2 or other suitable reinforce arranged around an aperture therein, through which passes a suitable link or clip 3 for connection with the tag T, as is shown clearly in Fig. 1. 90

The tag connecting clip 3 is here shown in the form of a coil of wire, but obviously it may be in any other form suitable for the purpose.

It will be understood that the closure 95 shown herein composed of the members A, B, *a*, *b* and *c* is purchased on the market and the attachment constituting this invention composed of the members 1 and 3 is applied to said closure in the manner above described 100 by being pasted thereon and carrying at its projecting end a fastener of any desired kind, for securing the parcel post tag T to the closure. This attachment is very simple and cheap to manufacture and yet provides 105 simple and convenient means for connecting the tag T to the closure.

The preferred embodiment of the invention is disclosed in the drawings and set forth in the specification, but it will be understood that any modifications within the 110 scope of the claimed invention may be made

in the construction without departing from the principle of the invention or sacrificing any of its advantages.

What I claim is:

- 5 1. The combination with a parcel post closure composed of two flaps adapted to be secured to the package and detachably connected with each other, of a strip adapted to extend transversely across one of said flaps 10 and to project at one end beyond the edge of the flap, said strip having means carried by the projecting end thereof to receive a tag fastener.

2. The combination with a parcel post closure composed of two flaps adapted to be secured to the package and to be detachably connected with each other, of a strip adapted to extend transversely across one of said flaps and to project at one end beyond the edge of the flap, said strip having a reinforced aperture in the projecting end thereof and a tag fastener mounted in said aperture.

In testimony whereof, I affix my signature hereto.

MORRIS COHEN.
